METHOD OF AND MEANS FOR FEEDING PAPER SHEETS

Application filed January 30, 1930, Serial No. 424,847, and in Germany March 9, 1929.

Paper sheet feeding devices are already known wherein the rear edge of the sheet is lifted from the pile by an auxiliary suction rod while the actual feeding of the sheet is effected by means of a suction rod which operates at the front edge of the sheet. There are also devices wherein one rear corner of the sheet is lifted by means of a single suction nozzle which forms part of a complicated sheet separating mechanism. Feeding devices wherein the sheet separation is effected at the rear end of the pile by mechanical sheet engaging elements aided by an air blast, are also known. These devices are applicable to flat piles only and have the defect that the sheet is compelled to travel the whole distance from the feeding device to the printing or like machine during the short time in which the printing takes place. A rapid feeding is, however, generally impracticable since thin sheets are apt to collapse at the machine register while thick sheets rebound, the registration being in each case liable to suffer. In order to avoid this difficulty it has been proposed to place a fanned-out pile in direct contact with the cylinder register of the machine, but this is not practicable since the sheets are too close together to allow the front sheet to be separated and properly positioned.

The difficulty is effectively removed by the present invention according to which the sheets are lifted at the rear edge, carried forwards into contact with the conveying elements, and advanced, during each operation of the machine, through part only of the distance between the machine and the feeder. Being thus advanced by degrees, the sheets can be moved sufficiently slowly for maintaining them in their proper place and positioned and delivering them to the machine in a satisfactory manner.

The device whereby the feeding method may be carried out is also provided with means for stopping the conveying elements independently of the feeder so as to retain remaining sheets on the conveying elements if the supply by means of the feeder should be interrupted or if it should be necessary to stop the supply for one reason or another.

Fig. 1 of the accompanying drawing rep-

resents a side view of a feeder working with fanned-out sheets,

Fig. 2 is a side view of the feeder working from a flat pile,

Fig. 3 is a view showing the distribution of the sheets on the conveying ribbons,

Fig. 4 is a view on an enlarged scale of some of the details of Fig. 2, and

Fig. 5 is a view of the device for stopping the conveying elements.

In the arrangement according to Fig. 1, fanned-out sheets are fed by tapes or bands 1 under a return roller 2 on to a table provided with a register 3. A suction rod provided with a plurality of nozzles 4 is operated in known manner and applied to the rear edge of the top sheet, near the register 3, as shown in Fig. 1. The rod then moves into the position shown in Fig. 2 and lifts the edge of the sheet into contact with feeding claws 7, the sheet being separated from the pile by a blast of air from nozzles 8. The feeding claws 7 are connected to a shaft 6 which is rocked by means of levers 5, as shown in Fig. 1 so as to push the front edge of the sheet over a guide plate 11 under rollers 9 which are operated by a rock shaft 10 so as to press the sheet against conveying tapes 17. The pressure of the claws against the edge of the sheet prevents the latter from dropping from the claws. The tapes 14 and further conveying tapes 18 are operated by a roller 27 so as to convey the sheet over the table 29 to the printing or like machine. The plate 11 is controlled by arms 12 which are pivoted at 13 and bear by means of rollers 14 against the paper pile on the return roller 2.

Each sheet is carried by the claws 7 under the rear edge of the next preceding one, and the sheets will therefore arrive at the printing machine as a thin continuous layer of overlapping sheets, as shown in Fig. 3.

The distance from the register 3 to the guide roller 14 corresponds to the length of a sheet, and the elements are adjustable for working with sheets of different lengths. A graduated scale may be provided for facilitating the adjustment.

In the case of a flat pile as shown in Fig. 2, the upper sheets of the pile are positioned by

- registers 15 which are connected to a rock shaft 16 and are turned back into the position shown by dotted lines in Fig. 4 each time a sheet is delivered by the claws 7. The shaft 16 is hollow and adapted to direct the air blast upwards against the delivered sheet so as to facilitate the delivery when the registers 15 take up the position shown dotted in Fig. 4.
- 10 The feed of paper to the machine may be interrupted by a stoppage of the conveying elements independently of the feeder. For this purpose motion is transmitted to the shaft 27 through the medium of a gear and clutch member 24 arranged rotatably and slidably on a driving shaft 25. Another clutch member 23, which is firmly secured to the driving shaft, is fitted with studs 31 adapted to engage in apertures in the clutch member 24 which is controlled by a spring 23 and by a double-armed lever 22 provided with an operating handle 30. The lever 22 is put into engagement with a spring-controlled catch 20 for maintaining the clutch members in engagement in opposition to the spring 23. The catch 20 is operable by means of an electromagnet for releasing the lever 22 so as to throw the conveying elements out of gear. The magnet circuit may be closed either by hand through the medium of a switch 19 or, in the case of a paper stoppage automatically through the medium of contact springs 28 placed on the table 29. The electric device may be replaced by a mechanical one.
- 35 We claim:—
1. A method of feeding paper sheets from a pile to a printing machine, consisting in lifting the sheets by suction from the pile at the rear edge, carrying each sheet forwards horizontally under the preceding sheet into contact with the feeding elements to form a thin continuous layer of overlapping sheets, advancing said layer, at each operation of the machine, through part only of the distance between the machine and the feeding device, and adding one sheet to the layer for each sheet taken away therefrom by the printing machine.
  - 50 2. A device for feeding paper sheets from a pile to a printing machine, comprising a conveying element, a suction rod arranged to engage and raise the edges of the sheets farthest away from the machine, reciprocating claws adapted to receive the raised edges of the sheets and to push the latter towards the machine into contact with the conveying elements, means for moving the latter so as to advance the sheets, at each operation of the machine, through part of the distance between the machine and the feeding device, and means for feeding the sheets in fanned-out condition to the suction rod.
  - 55 3. A device as claimed in claim 2 wherein the means for feeding the sheets in fanned-out condition to the suction rod, comprises a system of endless tapes and a deflecting roller, the last set of tapes arranged to move the sheets in opposite direction to that in which they are moved by the claws.
  4. The device claimed in claim 2 in combination with a register for positioning the sheets relative to the suction rod.
  5. A device as claimed in claim 2 in combination with means for stopping the conveying element independently of the feeder.
